[57] CLAIM

The ornamental design for a sheet film holder, as shown and described.

DESCRIPTION

FIG. 1 is a front, side and top perspective view of a sheet film holder showing my new design;

FIG. 2 is a rear, side and top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a side elevational view thereof from the left of FIG. 3;

FIG. 8 is a side elevational view thereof from the right of FIG. 3; and,

FIG. 9 is a front perspective view thereof, the broken line showing of a sheet film pack is for illustrative purposes only and forms no part of the claimed design.

FIG. 1

FIG. 2

FIG. 3

FIG. 4

FIG. 5

FIG. 6

FIG. 7

FIG. 8

FIG. 9
